DESIGN FOR A HOLLYWOOD STUDIO DOLL

William H. Sievers, Los Angeles, Calif.

Application July 31, 1933. Serial No. 48,886

Term of patent 3½ years

To all whom it may concern:

Be it known that I, WILLIAM H. SIEVERS, a citizen of the United States, residing at Los Angeles, in the county of Los Angeles and State of California, have invented a new, original, and ornamental Design for a Hollywood Studio Doll, of which the following is a specification, reference being had to the accompanying drawing, forming a part thereof.

Fig. 1 is the front view of the doll, showing my new design of the facial features.

Fig. 2 is a side view of the doll shown in Fig. 1. My invention relates to dolls and more particularly to the featuristic facial form of said dolls, said facial form comprising velour face surface, formed into characteristic features, having natural appearing eyes set within the eye orifices of the said facial form.

I claim:

The ornamental design for a Hollywood studio doll as shown, and described.

WILLIAM H. SIEVERS.
